UNITED STATES PATENT OFFICE.

WILLIAM H. HARTMAN, OF LOS ANGELES, CALIFORNIA, ASSIGNOR TO RANDALL
CONTROL AND HYDROMETRIC CORPORATION, OF LOS ANGELES, CALIFORNIA, A
CORPORATION OF CALIFORNIA.

ELEVATOR-DOOR-CONTROL SYSTEM.

Application filed December 2, 1920. Serial No. 427,669.

To all whom it may concern:

Be it known that I, WILLIAM H. HARTMAN, a citizen of the United States, and a resident of Los Angeles, county of Los Angeles, and State of California, have invented a certain new and useful Elevator-Door-Control System, of which the following is a specification.

The invention relates to elevator door control systems for use on automatic push button elevators.

An object of the invention is to provide an automatic push button elevator which cannot be operated when a shaft door is open or unlocked.

Another object of the invention is to provide an automatic push button elevator in which a shaft door cannot be opened unless the elevator car is opposite the door.

A further object of the invention is to provide an automatic push button elevator in which electrical contacts on the car for controlling the operation of the doors are eliminated.

A further object of the invention is to provide a simple, cheap, and efficient door control system for automatic push button elevators.

The invention possesses other advantageous features, some of which, with the foregoing, will be set forth at length in the following description where I shall outline in full that form of the invention which I have selected for illustration in the drawings accompanying and forming part of the present specification. In said drawings, I have shown one embodiment of the system of my invention, but it is to be understood that I do not limit myself to such form since the invention, as set forth in the claims, may be embodied in a plurality of forms.

Referring to said drawings:

Figure 1 is an elevation of an elevator shaft having two shaft doors, provided with the system of my invention.

Fig. 2 is a diagrammatic representation of the combination of elements entering into the system of my invention.

Fig. 3 is an elevation, partly in section, of the door lock in its open position, in association with the lock operating mechanism carried by the elevator car.

The door control system of my invention is particularly applicable to automatic push

button elevators in which the elevator car automatically moves to and stops at a floor predetermined by the pushing of a selected button. The present invention does not relate to the control system nor operating mechanism for automatic push button elevators and since such systems and mechanisms are well known to persons skilled in the art, they will not be described herein. In Fig. 1, I have shown an elevator shaft provided with two shaft doors 3 and 4 and an elevator car 5. The doors may be opened and closed by any suitable mechanism, or may be operated by hand, as is the case of the doors shown in the drawing. Means are provided for locking the doors in the closed position and for unlocking the door at the pre-selected floor, when the car arrives at the floor and these means serve also to prevent the operation of the elevator, when any shaft door is open or unlocked.

Arranged on the shaft structure at each floor is a lock casing 6 into which a bolt 7 on the door slides and in which the bolt is locked. Pivoted in the casing is a three-armed lever 8, the arm 9 of which is provided on its end with a hook or projection 12 which engages a seat 13 in the bolt 7, to lock the bolt against withdrawal from the casing. The lever is provided with an actuating arm 14, which is engaged by the actuating lever 15, projecting through the top of the casing and being provided on its upper end with a heavy roller 16. The lever is also provided with a laterally extending arm 17 which is provided on its free end with a stud 18 having a vertically disposed aperture, therethrough.

Rocking of the lever 15 moves the arm 9 to release the bolt 7, so that the door may be opened and means are provided within the casing for locking the arm 9 in the released position. Pivoted in the casing are two latches 21 and 22 which function to latch the lever 8 in released position. The lever 21 is provided with a notch 23 which engages a pin 24 on the arm 14 and the lever 22 has a notch 25 which engages a pin 26 on the arm 9, thus locking the lever in released position. The latches engage the end of the bolt 7 and fall into engagement with the pins as the bolt is withdrawn from the lock and are moved from engagement with the pins when the bolt is reinserted into the lock casing.

Means are provided for rocking the lever 15 to release the bolt when the elevator car reaches a floor, but this means is operative to release the bolt only at the floor predetermined by pushing the selected button. Pivotaly mounted on a standard on the elevator car are two bent levers 27, pivoted at one end to a shoe or cam 28 and pivoted at the other end to a link 29 carrying a counter-weight 31. The shoe or cam is vertically disposed and is positioned to contact with the roller 16 and operate the lever 15 when the car arrives at a floor. The shoe is normally held in extended position by the counter-weight, but is capable of being moved into retracted position. If the lever 15 is free to move, contact of the shoe with the roller will actuate the lever to release the bolt 7, but if the lever 15 is held against movement, then the shoe will be moved into retracted position as the elevator car passes the floor.

Means are provided for holding all of the levers 15 against movement except that one which is arranged at the floor selected by pushing the selected button. Disposed vertically in the elevator shaft is a wire or cable or rod 32 which passes through the apertures in the studs 18 and which is provided immediately above each stud with a stop or abutment 33 normally resting against the stud. The wire 32 is capable of vertical movement in the shaft and is moved vertically by the arm 17 when a lock is unlocked. The wire is connected at its upper end to a lever 34 and connected to the other side of the lever is a second wire 35, depending in the shaft and carrying a counter-weight 36 on its lower end. In order to unlock a shaft door, it is necessary that the wire 32 be moved vertically, but means are provided for preventing the vertical movement of the wire, except when the car is at the selected floor, so that as the car moves in the shaft the doors passed by the car are not unlocked. Secured to the lower end of the wire 32 is an armature 37 disposed in a solenoid 38 which is sufficiently powerful, when energized, to prevent the counter-weight 31 on the shoe from raising the arm 17. The solenoid is connected in the control circuit with the direction switch (not shown) which operates upon the pushing of a button to cause the car to move to the selected floor. The solenoid 38 is connected to the direction switch in such manner that the solenoid circuit is normally closed and is opened when the car reaches the selected floor. The car will, therefore, pass the other floors, without causing an unlocking of the door, but when the selected floor is reached, the solenoid circuit is opened permitting the wire 32 to be raised, thus permitting the door to be unlocked.

Means are further provided for preventing the car from being operated until every

shaft door is closed and locked. It has been shown that the unlocking of any shaft door is accompanied by a raising of the wire 32 and the wire 32 cannot then be lowered until the door is again closed and locked, at which time the wire 32 descends by gravity. Movement of the wire 35 is concurrent with movement of the wire 32 and I have employed the movement of the wire 35 to open and close a switch through which current is supplied to the car moving motor. Secured to the wire 35 and suitably insulated therefrom, is a contact bar 37' which is movable into and out of engagement with the contacts 38' and 39 of the power circuit and when the wire 32 is raised, wire 35 is lowered and the circuit between the contacts 38' and 39 is opened. This circuit is not again closed until the open door has been closed and locked.

I claim:

1. In an automatic elevator system having a car, a plurality of landings and doors for said landings, means for insuring that only that door can be opened, before which the car is to stop, comprising a lock for the selected door, means carried by the car for opening the lock, said means being adapted to perform by itself the opening of the lock, and means for holding the lock in closed position except when the car reaches the selected door.

2. In an automatic elevator system having a car, a plurality of landings, and doors for the landings, means for insuring that only that door can be opened before which the car is to stop, comprising locks for the doors, a single mechanical means for keeping all of the locks closed, electrically controlled means for rendering said means inoperative when the car approaches the selected door, and means carried by the car for opening the lock.

3. In an automatic elevator system having a car, a plurality of landings, and doors for the landings, means for insuring that only that door can be opened before which the car is to stop, comprising locks for the doors, means carried by the car for unlocking the doors, means cooperating with the locks for preventing the locks from being opened, and means responsive to the movement of the car to the selected door for rendering said last mentioned means inoperative.

4. In an elevator system having a car, means for moving the car, a plurality of landings, and doors for the landings, locks for the doors, a member arranged to keep the locks in closed position, and means for rendering said member inoperative in response to the arrival of a car at a selected position.

5. In an elevator system having a car, a plurality of landings, and doors for the

landings, locks for the doors, a member arranged to keep the locks in closed position, means responsive to the arrival of a car at a selected position for rendering said means 5 inoperative, and means for preventing the movement of the car responsive to the inoperative condition of the member arranged to keep the locks closed.

6. The combination of a car, a door, a 10 locking mechanism comprising a car-controlled releasing device having a car-actuated power-exerting member, and automatic means to restrain the releasing action of said device while the car is in motion.

15 7. The combination of a car, a door, a locking device including a member on the door, a movable latch member, cooperating stationary and movable members, the movable member being carried by the car and the 20 stationary member being in the path of the

movable member as the car travels, means for transmitting movement from the movable member to said movable latch member, and automatic means to restrain movement of said movable latch member when the car 25 is in motion, and to allow it to move when the car is at rest.

8. In a device of the class described, the combination of a locking mechanism comprising a member carried by the door, a 30 movable latch coacting with said member, a car-controlled power element operatively connected with said latch, and coacting surfaces on said door member and said latch member arranged to allow limited movement of the door member independently of said latch.

In testimony whereof, I have hereunto set my hand.

WILLIAM H. HARTMAN.
